Primary Examiner — Brett Miller
Assistant Examiner — Rani J Abdallah(57) **CLAIM**

The ornamental design for a container with lid, as shown and described.

DESCRIPTION

FIG. 1 is a front view of the first embodiment of a container with lid.

FIG. 2 is a right side view thereof;

FIG. 3 is a rear view thereof;

FIG. 4 is a top view thereof;

FIG. 5 is a top left perspective view thereof;

FIG. 6 is a bottom left perspective view thereof;

FIG. 7 is a front, exploded view thereof;

FIG. 8 is a right side, exploded view thereof;

FIG. 9 is a rear, exploded view thereof;

FIG. 10 is a top left perspective, exploded view thereof;

FIG. 11 is a bottom left perspective, exploded view thereof;

FIG. 12 is a top left perspective, exploded view thereof, showing a position.

FIG. 13 is a top left perspective, exploded view thereof, showing alternate position; and,

FIG. 14 is a top left perspective view of the second embodiment of a container with lid.

The broken lines are for environmental purposes only and form no part of the claimed design.
